UNITED STATES PATENT OFFICE.

ADOLPH SAMETZ, OF BROOKLYN, NEW YORK.

DESIGN FOR A PICTURE-FRAME.

SPECIFICATION forming part of Design No. 22,146, dated January 24, 1893.

Application filed November 28, 1892. Serial No. 453,428. Term of patent 7 years.

To all whom it may concern:-

Be it known that I, ADOLPH SAMETZ, a citizen of the United States, residing at the city of Brooklyn, Kings county, and State of New York, have invented and produced a new and original Design for Picture-Frames, of which the following is a specification, reference being had to the accompanying drawing, forming part thereof.

As shown in the drawing, the leading feature of my design is the shape of the picture frame which consists in the arrangement of the four narrow flaps or strips a, a', a^2, a^3 , respectively arched from the corners of the dis-

play opening to the corresponding corners b, b', b^2, b^3 , of the frame, each of said arched flaps being intermediate between the raised angular curved portions c, c', c^2, c^3 , the whole forming the top and sides of the display opening in the frame.

What I claim as new and desire to secure by Letters Patent is:

The design for a picture frame herein shown and described.

ADOLPH SAMETZ.
